CLAIM

The ornamental design for an automatic teller machine, as shown and described.

DESCRIPTION

FIG. 1 is a top, front, and right side perspective view of an automatic teller machine showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is another right side view thereof with the bottom touch display panel in an upright forward position, in which the dotted lines show the bottom touch display panel in its original position.

(Continued)

The broken lines shown in the drawings represent portions of the automatic teller machine that form no part of the claimed design.

APPLICATION NO. : 29/549039
DATED : June 6, 2017
INVENTOR(S) : Toshiaki Sato

Page 1 of 11

It is certified that error appears in the above-identified patent and that said Letters Patent is hereby corrected as shown below:

On the Title Page

Delete the title page and substitute therefore with the attached title page showing the corrected illustrative figure.

Delete the Page 2 and substitute therefore with the attached Page 2 showing the corrected number of drawing sheets in patent.

In the Drawings

Delete Drawing Sheets 1-5 and substitute therefore with the attached Drawing Sheets 1-8. FIGS 3-5 have been added to set of drawings.

Signed and Sealed this
Twenty-fourth Day of April, 2018

Andrei Iancu
Director of the United States Patent and Trademark Office
